UNITED STATES PATENT OFFICE.

JOHN W. GRAVES, OF LITTLE ROCK, ARKANSAS, ASSIGNOR TO THE AMERICAN COTTON COMPANY, OF NEW YORK, N. Y.

COTTON-PRESS.

SPECIFICATION forming part of Letters Patent No. 608,669, dated August 9, 1898.

Application filed February 25, 1898. Serial No. 671,679. (No model.)

To all whom it may concern:

Be it known that I, JOHN W. GRAVES, a citizen of the United States, residing at Little Rock, in the county of Pulaski and State of Arkansas, have invented certain new and useful Improvements in Cotton-Presses, (Case E,) of which the following is a specification.

My invention relates to various new and useful improvements in those cotton-presses 10 designed for making bales cylindrical in shape by convolutionally winding a continuous sheet or bat in layers around a spindle or core.

The objects of my invention are to provide 15 and produce improved driving mechanism for a cotton-press of the type referred to employing two movable compression or baling rolls working on opposite sides of a relatively-fixed core and to provide tension-producing mechanism for resisting the separation of such 20 rolls as the cotton accumulates on said core.

In order that my said invention may be better understood, attention is directed to the accompanying drawings, forming a part of 25 this specification, and in which—

Figure 1 is a side elevation from the driving side of the machine; Fig. 2, a similar view from the other side of the machine; Fig. 3, a plan view; Fig. 4, a section on the line 4 of 30 Fig. 5, and Fig. 5 a rear view.

In all of the above views corresponding parts are represented by the same numerals of reference.

11 represent the side frames of the machine, 35 each of which may be a single casting secured to suitable foundation beams or skids 22. The side frames 1 are connected together by suitable cross-beams 3, arranged in any suitable way.

40 4 is a core mounted centrally in the machine, so as to rotate with the forming bale, but held against lateral movements. In the present instance this core is provided at each end with a socket, into which is received a 45 spindle 5, carried on a screw-shaft 6. The said shaft at each side of the machine is carried in a rotatable bearing-box 7, mounted in the side frames. Each bearing-box 7 is preferably formed with an enlarged disk 8 thereon for guiding the cotton and for building up the ends of the bale, as is common.

In order to release the core 4, the screw-shafts 6 are rotated, so as to withdraw the spindles 5 from the sockets in the end of the core, as will be understood. 9 and 10 represent cylindrical baling-rolls mounted on each side of the core 4 and co-operating therewith, so as to wind the sheet or bat in convolutional layers on said core. The shaft 11 of each of these rolls is carried in suitable bearing-boxes 12, movable in slots 13, formed in the side frames 1 of the machine in line with the core 4, whereby as the cotton accumulates on said core the rolls will separate, the boxes 12 moving in the slots 13, and thereby allowing for 65 this separation. In order to rotate the baling-rolls, I prefer to employ a novel form of worm-gearing by which the lateral movements of the baling-rolls will be permitted without affecting the rotation thereof. 70

14 represents a main driving-shaft mounted in suitable boxes 15, suitable provision being made in one or all of said boxes to receive the end thrust of said shaft.

Rigidly keyed to the shaft 11 of each baling-roll is a worm-gear 16, which gears engage with and are driven by elongated worms 17 on the main driving-shaft 14. Power is applied to said shaft by a suitable pulley 18, by which said shaft will be driven, so as to rotate the 80 worm-gears 16, and thereby drive the baling-rolls in the same direction and with the same peripheral speed. By employing two elongated worms co-operating with two laterally-movable baling-rolls the said rolls will be allowed to separate with the enlarging bale, since the worm-gears 16 will move backward on the elongated worms 17, as will be understood. 85

In order to apply tension to the baling-rolls 90 9 and 10, so as to resist the separation of such rolls with the enlarging bale, I employ a tension-producing shaft 19 at each side of the machine. Each of said shafts is carried in suitable bearing-boxes 20 and extends parallel 95 with the slots 13 in the side frames of the machine. On each end of each of the shafts 11 is loosely carried a nut 21, which engages with a screw 22 on the shaft 19. These screws are oppositely arranged at each side of the 100 machine—i. e., one is right-handed and the other is left-handed—whereby the movement

of the nuts carried by the shaft of the baling-roll 9 will effect the same direction of rotation of the shafts 19 as the movement in the opposite direction of the nuts carried by the 5 shaft of the baling-roll 10. The resistance of the shafts 19 to the turning influence of the nuts 21, working on the screws 22, provides for the imposition of the necessary pressure upon the baling-rolls; but, if desired, a positive resisting device, such as a brake, may be applied to one or both of the shafts 19 to increase the tension.

In order to produce simultaneous rotation of the shafts 19, I prefer to connect them 15 together by an ordinary sprocket-chain 23, and in order to return the baling-rolls 9 and 10 to their original positions into contact with the core 4 one of the tension-producing shafts may be provided with a suitable pulley-wheel 20 24 thereon, to which power may be applied for this purpose.

The operation of my improved cotton-press is as follows: At the starting of the operation the baling-rolls 9 and 10 are brought into contact with the core 4, which is supported on the spindles 5 of the screw-threaded shafts 6. Power is applied to the pulley-wheel 18, so as to rotate the shaft 14, and thereby, through the worm-gearing, to drive the baling-rolls 9 and 30 10 in the same direction and with the same peripheral speed. A sheet or bat of cotton is now fed to the core 4 and will be wound up thereon in convolutional layers in the well-known way. As the cotton accumulates on 35 said core the baling-rolls 9 and 10 will be separated, and this separation will be resisted by the movement of the nuts 21 in rotating the shafts 19. When the bale is finished, the supply of cotton is cut off and the bale covered 40 by a suitable wrapping material, after which the core is released by withdrawing the screw-threaded shafts 6, and the bale will drop out of the machine by its weight. A new core is now applied in place, and power being applied 45 to the pulley-wheel 24 the tension-producing shafts 19 will be driven in the opposite direction, thereby returning the baling-rolls to their original positions in contact with the core, and the press will then be in 50 condition for the starting of a new bale.

Having now described my invention, what I claim as new, and desire to secure by Letters Patent, is as follows:

1. In a cotton-press, the combination of a 55 core mounted in stationary boxes, two baling-rolls oppositely disposed with relation to said core and mounted in movable bearing-blocks, a worm-gear carried by the shaft of each of said baling-rolls, a main driving-shaft located 60 in line with said worm-gears, and two elongated worms on said shaft with which said worm-gears coöperate, substantially as set forth.

2. In a cotton-press, the combination of a 65 baling-roll, a core mounted adjacent to said baling-roll, a second baling-roll coöoperating with said core and mounted on the other side

thereof in movable bearing-boxes, a nut loosely mounted on each end of the shaft of the second baling-roll, and tension-producing 70 shafts having screws thereon with which said nuts coöperate, substantially as set forth.

3. In a cotton-press, the combination of a baling-roll, a core mounted adjacent to said baling-roll, a second baling-roll coöoperating 75 with said core and mounted on the other side thereof in movable bearing-boxes, a nut loosely mounted on each end of the shaft of the second baling-roll, tension-producing shafts having screws thereon with which said nuts coöperate, and means for causing said tension-producing shafts to rotate simultaneously, substantially as set forth.

4. In a cotton-press, the combination of a baling-roll, a core mounted adjacent to said 85 baling-roll, a second baling-roll coöoperating with said core and mounted on the other side thereof in movable bearing-boxes, a nut loosely mounted on each end of the shaft of the second baling-roll, tension-producing 90 shafts having screws thereon with which said nuts coöperate, and a sprocket-chain connecting said shafts, whereby the same will rotate simultaneously, substantially as set forth.

5. In a cotton-press, the combination of a 95 baling-roll, a core mounted adjacent to said baling-roll, a second baling-roll coöoperating with said core and mounted on the other side thereof in movable bearing-boxes, a nut loosely mounted on each end of the shaft of the second baling-roll, tension-producing 100 shafts having screws thereon with which said nuts coöperate, and means for reversely rotating said shafts, substantially as set forth.

6. In a cotton-press, the combination of a 105 baling-roll, a core mounted adjacent to said baling-roll, a second baling-roll coöoperating with said core and mounted on the other side thereof in movable bearing-boxes, a nut loosely mounted on each end of the shaft of the second baling-roll, tension-producing 110 shafts having screws thereon with which said nuts coöperate, means for causing said tension-producing shafts to rotate simultaneously, and a pulley-wheel connected to one of 115 said shafts for reversely rotating the same, substantially as set forth.

7. In a cotton-press, the combination with a core mounted in stationary bearing-boxes, of two baling-rolls coöoperating with said core 120 and mounted in movable bearing-boxes, a nut loosely mounted on each end of the shaft of each of said baling-rolls, two tension-producing shafts, and screws on said tension-producing shafts with which said nuts coöperate, 125 substantially as set forth.

8. In a cotton-press, the combination with a core mounted in stationary bearing-boxes, of two baling-rolls coöoperating with said core and mounted in movable bearing-boxes, a nut 130 loosely mounted on each end of the shaft of each of said baling-rolls, two tension-producing shafts, screws on said tension-producing shafts with which said nuts coöperate, and

means for causing said tension-producing shafts to rotate simultaneously, substantially as set forth.

9. In a cotton-press, the combination with a core mounted in stationary bearing-blocks, of two baling-rolls coöperating with said core and mounted in movable bearing-blocks, a nut loosely mounted on each end of the shaft of each of said baling-rolls, two tension-producing shafts, screws on said tension-produc-

ing shafts with which said nuts coöperate, and a sprocket-chain connecting said tension-producing shafts, whereby they will be simultaneously rotated, substantially as set forth.

This specification signed and witnessed this 15
12th day of February, 1898.

JOHN W. GRAVES.
